UNITED STATES PATENT OFFICE.

HATTIE R. OVENSHIRE, OF MINNEAPOLIS, MINNESOTA, ASSIGNOR OF ONE-THIRD TO CHARLES E. OVENSHIRE AND ONE-THIRD TO DONALD DEE, BOTH OF MINNEAPOLIS, MINNESOTA.

GARMENT SUPPORTER.

Application filed February 3, 1926. Serial No. 85,707.

This invention relates to improvements in garment supporters designed particularly for use in wardrobe trunks although adapted for use also in closets and other places.

5 The object of the invention is to provide a supporter that will be simple and durable in construction and capable of being used in trunks or closets of varying widths and which shall be capable both of bodily movement and a free swinging action upon its supporting rods or bars.

10 The invention consists generally in the constructions and combinations hereinafter described and particularly pointed out in 15 the claims.

In the accompanying drawings forming part of this specification,

Figure 1 is a perspective view of a portion of a wardrobe trunk showing my 20 improved garment supporter arranged therein;

Figure 2 is a vertical section of the trunk showing two of the garment supporters arranged therein;

25 Figure 3 is a perspective view of the garment supporter; and

Figures 4 and 5 are detailed perspectives showing modified constructions.

In the drawings, 2 represents a portion 30 of a wardrobe trunk of any suitable size and construction. The general supporter comprises a garment sustaining frame 3 preferably provided with sloping members 4 and a horizontal member 5. As here shown, the frame 3 is preferably formed of a single rod or wire bent into the form shown and having its ends upwardly extending and secured within a bracket 6, which is preferably provided with a sleeve 7, through 35 which passes a horizontal bar 8, and to which the sleeve, preferably, is rigidly secured. I have shown the bar 8 of tubular form, and arranged in each of its open ends is a sliding bar 9 provided with a hook 10.

40 These bars are arranged to slide freely in the ends of the tubular bar 8 and may therefore be moved in and out so as to adapt the supporter for use in trunks or closets of varying widths. The trunk or closet in 45 which the supporter is to be used is provided, near its side walls, with the horizontal bars 12 secured in position by suitable brackets 13 and 14.

In Figure 4 I have shown the bar 8 in the

form of a solid rod with the hook 10 secured to a short tubular section 15 which telescopes over the end of the bar 8. In Figure 5 I have shown the bar 8 of rectangular sleeve 16 to which the hook 10 is secured.

The member 5 of the garment supporting frame is substantially parallel to the bar 8 so that an article of clothing may be supported upon said member by being folded and hung thereon. The sloping members 4 constituting the upper part of the garment holding frame are adapted to carry thereon coats and similar articles, the sloping members coming within the upper or shoulder parts of said garments.

This garment supporter is capable of being moved to any desired position within the trunk on the bars 12 and the garments hang freely thereon, the frame being capable of swinging back and forth as indicated by dotted lines in Figure 4.

With this structure the garments may be placed on the supporters either before the supporters are put in position in the trunk, or they may be placed thereon while the supporters are in position on the supporting bars. The garments are also readily accessible without removing them from the trunk. As the supporters are capable of a swinging action the clothes may very easily be made to hang smoothly thereon so that when the trunk is closed and the clothes are compacted together there will be little liability of their becoming jammed or wrinkled. As the supporters are capable of being used in trunks of varying widths they may be made of a standard size and adjusted by the user to accommodate the width of the trunk in which it is desired to place the same.

I do not limit myself to the details of construction as the same may be changed in any particular without departing from my invention.

I claim as my invention:

1. A garment supporter comprising a 100 tubular element, a clothes supporting frame secured to said tubular element and provided with oppositely extending sloping members having their lower ends joined by a horizontal member, and bars, provided with hooks 105 at their ends, and slidably supported in the opposite ends of said tubular element.

2. A garment supporter comprising a hori-

zontally extending main bar, a clothes sustaining frame secured to said main bar and provided with oppositely extending sloping members having their lower ends joined by a 5 horizontal member, and longitudinally extending bars, provided with hooks at their ends, and slidably and rotatably supported in the opposite ends of said main bar.

3. The combination with a trunk having 10 supporting means adjacent the walls thereof, of a garment hanger adapted to be suspended between said supporting means and comprising an elongated member, a device adapted to fit into a garment and having means for 15 connection with the middle portion of said elongated member to be supported thereby, and hook members loosely engaging said supporting means and having end portions adapted to slide in said elongated member 20 and rotate thereon whereby said elongated member is free to slide and rock on said hook members and accommodate itself to different positions of the garment in the trunk.

25 4. A device of the class described, comprising

ing a tubular member having a hanger frame 30 rigidly connected thereto, and a pair of rod-like elements telescopically engaged in said tubular member from opposite ends, each rod having a terminal hook adapted for sliding attachment to a support, the terminal 35 portions of said telescopic supporting elements, when attached, being separated by a distance substantially greater than the length of the tubular member, to permit translative adjustment of the tubular member thereon 40 in either direction.

5. In combination with a pair of spaced supports, a tubular member of substantially less length than the distance between said supports, and having a hanger frame secured 45 thereto, and rod elements, one telescopically engaging said tubular member at each end, each rod being engaged with a respective support to hold said rods against lengthwise translation.

In witness whereof, I have hereunto set my hand this 29th day of January, 1926.

HATTIE R. OVENSHIRE.
